UNITED STATES PATENT OFFICE.

JOHN C. B. JARVIS, OF NEW YORK, N. Y.

COMBINED ASH-CAN AND LAWN-ROLLER.

1,088,582.

Specification of Letters Patent.

Patented Feb. 24, 1914.

Application filed April 19, 1912. Serial No. 691,792.

To all whom it may concern:

Be it known that I, JOHN C. B. JARVIS, a citizen of the United States, and a resident of the city of New York, borough of Brooklyn, in the county of Kings and State of New York, have invented a new and Improved Combined Ash-Can and Lawn-Roller, of which the following is a full, clear, and exact description.

10 My invention relates to ash cans, and it has for its object to provide one having a cover and provided with a sleeve supported by the bottom of the can and the cover for receiving an axle so that when the arms and 15 the tongue are pivotally connected with the axle, the ash can may be rolled to transport the ashes, and the ash can may also be filled with ashes, and may be used as a roller for rolling the lawn, tennis courts, etc.

20 Additional objects of the invention will appear in the following complete specification, in which the preferred form of the invention is disclosed.

In the drawings similar characters of reference indicate corresponding parts in all the views, in which—

Figure 1 is a perspective view showing my improved ash can; Fig. 2 is a transverse sectional view of a modified form of the can; 30 Fig. 3 is a longitudinal sectional view of the can shown in Fig. 1 of the drawings; and Fig. 4 is a longitudinal sectional view of the can shown in Fig. 2 of the drawings.

By referring to the drawings it will be 35 seen that a drum 5 is provided, in which the ashes may be disposed, the outer surface of the drum serving as a roller, so that the ashes in the drum may be conveniently transported, it being also possible to use the drum 40 as a roller for pressing down the ground, the sides of the outer surface being disposed substantially parallel so that the drum may be used in this manner.

The bottom 6 of the drum is held in place 45 by rivets 7, or other similar means, this bottom 6 being provided with an orifice 8, with a flange member 9 secured to the bottom 6, around this orifice, the flange member 9 being provided with a threaded orifice 10, 50 in which meshes the thread 11 at the terminal of a sleeve 12, the sleeve being disposed in the drum 5, and serving as a bearing for the axle 13. The drum 5 is provided with a cover 14, which has an orifice 15, and a 55 flange member 16, secured to the cover 14

around the said orifice 15. The flange member 16 has a thread 17, which meshes with a thread 18 on the sleeve 12, so that when the cover 14 is disposed on the drum 5, with the sleeve 12 in alinement with the threaded orifice 17 in the flange member 16, the cover 14 will be secured to the sleeve 12, and to the drum 5, by rotating the cover 14 relatively to the said drum 5. The axle 13, which is disposed in the sleeve 12 has terminals 19, which project beyond the bottom 6, and the cover 14, these terminals 19 being disposed in the orifices 20 in the arms 21, so that when the arms 21 are moved by the tongue 22, to which they are secured by the cross member 23, the drum 5 will be rotated and will be drawn along the ground.

The axle 13 has a head 24, at one end, and is provided with a threaded terminal at the other end, with which a nut 25 meshes, this means being provided so that the axle 13 may be readily withdrawn from the sleeve 12. When the drum 5 is being filled with the ashes, the nut 25 is removed, so that the axle 13 may be withdrawn from the sleeve 12, and the arms 21 may be removed from the drum 5, to permit the removal of the cover 14. After the drum 5 has been filled with the ashes, the cover 14 is replaced, and its threaded member 16 is rotated, so that it will engage the thread 18 on the sleeve 12, and will lock the cover 14 to the said sleeve 12, and to the drum 5. This having been done, the arms 21 are disposed in position, one at the head or bottom 6, and the other at the cover 14, when the axle 13 may be disposed in the sleeve 12, and may be secured in place by the nut 25.

In the modified construction shown in Figs. 2 and 4 of the drawings, a drum is provided in two section 5^a, each section having an inner wall 26, with a groove 27, in this inner wall, these inner walls being normally disposed against each other. Secured in each of the grooves 27 there is a sleeve section 28, these sleeve sections 28 uniting to form a bearing sleeve when the drum sections 5^a are disposed in position with their inner walls 26 against each other. Each of the drum sections 5^a is provided with a head or bottom member 29, the bearing sleeve sections 28 projecting through an opening 30 between the said head members 29, when the drums 5^a are disposed in the position shown in Figs. 2 and 4 of the drawings.

Disposed over the head or bottom 29 there is a false bottom 31, which is provided with flanges 32 which engage the sleeve bearing sections 28 to hold them together, and in position. This false bottom 31 is provided with an orifice 33, through which a terminal of an axle 34 projects, this axle 34 being disposed in the bearing sleeve members 28. The other ends of the drum sections 5^a are normally closed by a cover 35, which is provided with flanges 36 which engage the inner walls 26 at the grooves 27, for holding the inner walls 26 together, and the drum sections 5^a in position. This cover 35 also has an orifice 37, through which a terminal of the axle 34 projects. The axle 34 has threaded terminals with which mesh the nuts 38, after the axle 34 has been disposed through the orifices in the arms 21. These arms 21 are connected by the transverse member 23, to which is secured the tongue 22, in the manner already described.

In using the form of invention shown in Figs. 2 and 4 of the drawings, the drum sections 5^a may be filled and may be used separately, the drum sections being held together at one end by the false bottom 31, and the flange members 30 on the false bottom, which engage the bearing sleeve sections 28. At the other end the drum sections 5^a are held together by the flanges 36, which engage the inner walls 26 at the grooves 27, the cover 35 also having a peripheral flange 39, which engages the peripheries of the drums 5^a. The false bottom 31 also has an outer flange 40 which engages the peripheries of the outer drums 5^a.

Having thus described my invention I claim as new and desire to secure by Letters Patent:

1. In an article of the class described, a drum having a head with an orifice at one end, a removable cover with an orifice normally disposed over the other end, a sleeve disposed in the drum and connected with the head and the cover about the orifice, an axle disposed in the sleeve, and having terminals extending through the orifices, and arms connected with the terminals.

2. In an article of the class described, a drum having a head at one end, a removable cover for closing the other end, arms disposed at the outer sides of the head and cover and pivotally connected therewith for holding the cover relatively to the head while permitting the drum to rotate relatively to the arms.

3. An article of the class described, a drum having a head at one end, a removable cover normally disposed over the other end, a member disposed in the drum and secured

to the end, and the cover, arms and means for pivotally connecting the arms relatively to the member.

4. In an article of the class described, a drum having a head at one end and provided with an opening, a removable cover for closing the other end and provided with an opening, arms disposed at the outer sides of the head and cover, an axle extending through the drum and provided with terminals projecting through the openings, and means on the axle for normally engaging the arms for holding them in position which permit the rotation of the drum relatively to the arms while preventing the removal of the cover.

5. In an article of the class described, a drum in two sections with each section provided with a longitudinal groove on an inner wall, the grooves normally uniting to form a bearing, an axle disposed in the bearing and having terminals projecting therefrom, and arms connected with the terminals.

6. In an article of the class described, a drum in a plurality of sections open at one set of ends, and with each section provided with a longitudinal groove on an inner wall, the grooves uniting to form a bearing, a cover for the said set of ends having flanges for engaging the inner walls for assisting in holding the sections together, there being an orifice in the cover for registering with the bearing formed by the grooves, an axle disposed in the bearing and in the orifice in the cover, and arms connected with the axle.

7. In an article of the class described, a drum in a plurality of sections, open at one set of ends, with each section provided with a longitudinal groove on an inner wall, the grooves uniting to form a bearing, a cover for the said set of ends having an orifice, a sleeve bearing in sections, each section being secured in the groove in one of the drum sections and projecting from the drum sections at the other set of ends, a false bottom, the false bottom at the said other set of ends having flanges for engaging the projecting portions of the sleeve bearing, and an orifice in alignment with the opening in the sleeve bearing, an axle disposed in the sleeve bearing and projecting from the orifices in the cover and in the false bottom, and arms disposed at the false bottom and at the cover and connected with the axle.

In testimony whereof I have signed my name to this specification in the presence of two subscribing witnesses.

JOHN C. B. JARVIS.
